(57) **CLAIM**

The ornamental design for an extraction unit for a cooking system as shown.

DESCRIPTION

FIG. 1 is a perspective view of an extraction unit for a cooking system in accordance with our design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines shown in the figures depict portions of the extraction unit for a cooking system that form no part of the claimed design.

The evenly-spaced broken lines shown in the figures depict portions of the extraction unit for a cooking system that form no part of the claimed design. The dot-dash broken line in the drawings depict a boundary line. The boundary line and surface within the boundary line form no part of the claimed design.
